CLAIM

The ornamental design for a light fixture, as shown and described.

DESCRIPTION

FIG. 1 is a front perspective view of a light fixture according to the present invention;

FIG. 2 is a rear perspective view of the light fixture;

FIG. 3 is a front view thereof;

FIG. 4 is a right side view thereof;

FIG. 5 is a rear view thereof;

FIG. 6 is a left side view thereof;

FIG. 7 is a top view thereof; and,

FIG. 8 is a bottom view thereof.

Throughout the drawings the broken lines depict portions of the light fixture that form no part of the claimed design.

1 Claim, 5 Drawing Sheets
